[57] CLAIM

The ornamental design for a necktie, as shown and described.

DESCRIPTION

FIG. 1 is a front elevational view of a necktie showing my new design, the rear view being identical;
FIG. 2 is a front elevational view of a second embodiment thereof;

FIG. 3 is a top plan view of both embodiments;
FIG. 4 is a side elevational view of both embodiments;
and

FIG. 5 is a bottom plan view of both embodiments.
The undisclosed rear view of the second embodiment is plain and unornamented.

FIG. 1

FIG. 2

FIG. 3

FIG. 4

FIG. 5
